[57] ABSTRACT

A plug-in main contact and blast valve unit is inserted or withdrawn through the end of a housing or tank of a gas-insulated substation arrangement. Conducting self-aligning ring and compensating securing means adjust for angular and linear tolerance variations. Bolting means between the contact housing, elbow, and header include an adjustable seating sleeve on each side of the elbow for positioning the contact and valve unit for both horizontal and vertical adjusting movement in the tank to obtain the necessary mechanical and electrical clearances. Special guides and tapering arrangements facilitate the alignment procedure and sealing arrangement. A service unit is provided to facilitate a guiding and positioning insertion and withdrawal of the contact and blast valve unit into and out of the tank.

PLUG-IN CONTACT AND BLAST VALVE UNIT

SUMMARY OF THE INVENTION

This invention relates to substation electrical structures such as a high voltage, gas-insulated circuit breaker for both indoor and outdoor use.

Present known devices are extremely difficult to service and require extensive dismantling of the unit in order to perform the necessary servicing of the circuit contacts and to inspect the blast valve and associated mechanism. Furthermore, known gas-insulated circuit breakers and the associated blast valve are constructed as two distinct physically unrelated components each of which require separate handling, alignment and adjustment. This type of construction results in a structure having many components which complicate manufacturing and assembly.

It is therefore desirable to provide an improved gas-insulated circuit breaker constructed and arranged to have a unitized contact, gas blast valve and mechanism assembly which simplifies manufacturing, assembling and servicing.

A gas-insulated circuit breaker in accordance with the present invention comprises an enclosed gas filled tank or housing at relatively low pressure having a centrally located source of insulating gas at relatively high pressure, said gas is utilized both as an insulating medium and also as an interrupting medium. The source of gas at relatively high pressure is directed to a centrally located distribution housing or casting which serves as a gas flow directing member to a gas valve device. The gas blast valve device as well as the interrupting contacts and mechanism are deployed in single component arrangement that can be inserted or withdrawn from the central distribution housing externally from the ends of the tank. The arrangement eliminates the necessity of dismantling the tank and its internal elements when servicing is found necessary and also eliminates the necessity of having service personnel enter the tank to dismantle or service the breaker or blast valve unit. Insertion of the contact and blast valve unit into the distribution casting in gas sealed relationship is facilitated by the provision of a female tapered end which mates with a male outlet construction that includes a sealing ring in the distribution casting. Bolting means secure the contact and blast valve unit at its lower end to the distribution casting and are located so as to effectively resist the large forces exerted by the high pressure gas. Bolting means at the top consist of self-aligning locating and conducting pads which compensate for angular and linear tolerance variations. All securing devices are accessible by service personnel from the exterior of the tank. Actuating mechanism associated with the main contact and blast valve permit precise external adjustment and synchronization of contact and valve operation before insertion into the tank. Guided insertion and withdrawal of the contact and blast valve unit into and out of operating position is easily accomplished by means of a light-weight dual rail device which facilitates handling of the relatively heavy contact and blast valve unit.

DESCRIPTION OF THE DRAWINGS

FIG. 1 is a view in elevation of a substation circuit breaker installation utilizing a plurality of series related gas-insulated circuit breakers in which the present invention is incorporated;

FIG. 2 is a plan view of one phase of the substation circuit breaker arrangement shown in FIG. 1;

FIG. 3 is an enlarged fragmentary detailed view of the control portion of one of the gas-insulated circuit breakers showing one of the main contacts and its associated blast valve in operating association with the central high pressure gas distribution housing;

FIG. 4 is a view similar to FIG. 3 showing the circuit breaker main contact and blast valve unit separated from the central high pressure gas distribution housing and upper support;

FIG. 5 is an enlarged detailed view in horizontal section taken in a plane represented by the line V—V in FIG. 3 showing an adjustable conducting and mounting pad;

FIG. 6 is an enlarged detailed view in horizontal section taken in a plane represented by the line VI—VI in FIG. 3 showing the arrangement of an adjustable seating sleeve and associated locking bolt for positioning the contact and valve unit both horizontally and vertically; a T-wrench being illustrated for tightening or loosening the belt from the exterior of the tank, with an adaptor for adjusting the seating sleeve;

FIG. 7 is a view partly in horizontal section and partly in plan through one end of a circuit breaker tank showing the service unit in position for withdrawing the contact and blast valve unit;

FIG. 8 is a view partly in vertical section and partly in elevation showing the service unit arrangement depicted in FIG. 7, the contact and blast valve unit being shown in broken lines as it would appear when withdrawn from the tank;

FIG. 9 is a view partly in horizontal section and partly in plan similar to FIG. 7 with the service unit arranged for inserting the contact and blast valve unit into operating position within the tank;

FIG. 10 is a view partly in vertical section and partly in elevation showing the service unit arranged for insertion with the insertion mechanism fully extended after completing the operation of inserting the contact and blast valve unit into operating position;

FIG. 11 is a view in elevation of the contact and blast valve housing the glass flow passages and the three-point support arrangement; and,

FIG. 12 is an enlarged fragmentary detailed view of contact and blast valve unit of FIG. 3 modified to accommodate a single interrupter arrangement for minimal interrupting capacity.

DESCRIPTION OF THE INVENTION

Referring now to the drawings, and more particularly to FIGS. 1 and 2 thereof, there is depicted a substation installation 20 comprising a plurality of series connected gas-insulated circuit breakers 21, 22 and 23. Each circuit breaker is substantially identical; and thus, a description of the circuit breaker 22 will also apply to the breakers 21 and 23. The circuit breaker 22 includes a pair of contact and gas blast valve units 26 and 27 which are electrically connected in series through a centrally located support housing or casting 28. The contact and gas blast valve units 26 and 27 as well as

the centrally disposed support housing 28 are disposed within a gas-tight tank 31 having an insulating gas at relatively low pressure therein. Synchronous operation of the movable main contact 32, FIG. 3, and of the gas blast valve 33 of the unit 26 is effected by operating linkage 35.

Gas at a relatively high pressure is contained within a supply tank 36 which is secured in gas-tight relationship to a depending mounting flange 37 integrally formed with the bottom of the tank 31. A supply of gas from the supply tank 36 is directed to the central distribution header 104 by means of a supply pipe 38 which has gas-tight fitting relationship with the header 104 and the tank 36.

Support for both contact and valve units 26 and 27 as well as for the relatively heavy central support consisting of housing 28, support 28A and header 104, and the associated operating linkage 35 and the identical operating linkage (not shown) associated with the contact and valve unit 27 is afforded by means of a downwardly extending internal insulator housing or pipe 39 which is secured to a sealing closure plate 41 carried by a circular housing 42 that extends upwardly from the top of the tank 31. The depending end of the insulator pipe 39 receives a collar portion 43 of the support housing 28 and is locked thereto by means of an expanding collet 44. Thus, the entire weight of the operating contact and valve units 26 and 27, the support housing 28, as well as both operating linkages, is supported by the insulator pipe 39. To counteract the blast and other vibrational effects on the support housing 28 the insulated high pressure gas feed pipe operates through parts 104 and 28A to impart a stabilizing effect to the housing 28.

As previously mentioned, operation of the movable contact 32 and opening of the blast valve 33 of the contact and valve unit 26 as well as the identical counterparts (not shown) associated with the contact and valve unit 27 is accomplished through the operating linkage 35 and identical operating linkage (not shown) associated with the unit 27. These linkages are actuated by means of a common actuating rod 46 supported for reciprocal movement in the pipe 39. As shown, the lower end of the rod 46 is pivotally connected to a pair of tie links 47 and 48. The link 47 has an operative connection to the linkage 35 while the link 48 is operatively connected to the linkage (not shown) associated with the unit 27. As viewed in FIG. 3, upward movement of the rod 46 will effect opening movement of the movable contacts and the blast valves associated with the units 26 and 27. This movement is imparted to the rod 46 by rotation of an operating shaft 49 which is connected through suitable linkage 51 to the upper end of the rod 46. As shown in FIGS. 1 and 2, the operating shaft 49 is rotated by a connecting rod and lever system 49A extending across the top of the three circuit breakers 21, 22 and 23 within a protective housing or tube 52. At the left end of the phase 20, as viewed in FIGS. 1 and 2, the connecting rod system 49A terminates in a direction change box 53 in which is an operative connection with a vertical shaft 54. The vertical shaft 54 extends downwardly from the direction change box 53 into a control cabinet 56. Within the control cabinet 56 there is an operating mechanism such as a high speed mechanically trip-free pneudraulic operating mechanism 57 which is operatively connected to effect reciprocal motion of the vertical shaft 54. Thus, opera-

tion of the mechanism 57 upon a proper signal from a source (not shown) will cause the mechanism to operate in one direction to effect the opening of the contacts and valves. On the other hand, operation of the mechanism 57 in the opposite direction, in accordance with the proper signal, will effect the closing of the contacts.

As previously mentioned, the contact and blast valve units 26 and 27 are constructed and arranged for guided insertion and withdrawal from the tank 31 through an adjacent service end of the tank. Contact and blast valve unit 26 is shown in FIGS. 3 and 4, and a description of this unit will also apply to the unit 27. As shown, the unit 26 comprises an insulator contact tube or casing 61 in which a fixed contact support tube 62 is disposed. Resilient inwardly biased contact fingers 63 are supported in the right end of the tubular support 62. Surrounding the resilient contact fingers 63 is a gas flow deflector 64. Supported for axial movement into and out of engagement with the resilient contact fingers 63 is the movable tubular contact 32 that is supported by a fixed nose piece 67 containing transfer contact fingers 63A. The nose piece 67 is secured to the extending end of a tubular projection 68 integrally formed with a main contact housing 69. For supporting the main movable contact 32 for guided axial reciprocation in the tubular projection 68 a circular guide 71 is integrally formed around the contact at the right end thereof. Pivotally attached to the right end of the tubular movable contact 32 is a rod 72 which has its opposite end connected to the contact operating linkage 35. A corona shield 73 surrounds the right end of the contact insulator housing 61. A similar corona shield (not shown) surrounds the extreme left end of the contact insulator housing 61.

In order to more effectively provide the contacts of unit 26 with an adequate supply of high pressure gas at the area of arcing at the occurrence of contact separation, an efficient gas valve and flow directing arrangement is provided. To this end an elbow housing 76 is provided in which the blast valve 33 is operatively carried. As shown in FIG. 3, the blast valve 33 is secured to the downwardly facing bottom plate 77 formed on the main contact housing 69. The bottom flange 77 of main contact housing is provided with an opening 78 which communicates with a semicircular or horseshoe configured gas passage 79. Communication between the opening 78 and the horseshoe configured passage 79 is effected at the toe portion of the passage 79 so that gas flow is around the tubular contact guide projection 68 of the main contact housing 69. Forwardly or to the left, as viewed in FIG. 11, the horseshoe configured gas passage 79 communicates with a circular gas flow chamber 81 which surrounds the right end of the contact guide projection 68 and is in communication with a multi-passaged circular gas flow director 82 that surrounds the left end of the contact guide projection 68. Thus, when the valve 33 is displaced from the valve seat 33A, gas at a relatively high pressure will flow through sealing plate 77A into the transverse passage 78 and thence into the horseshoe configured passage 79. The horseshoe configured passage 79 operates to change the direction of flow of the gas where it is directed into the communicating circular passage 81. Since the gas flowing in the horseshoe configured passage 79 is at a relatively high pressure and its direction of flow is being changed by the passage 79, turbulence

in the flow may occur. Thus, the multi-passaged director 82 serves to straighten the flow of the gas to remove turbulence, thereby retaining the high velocity of the gas flow.

To open the valve 33 is sequential synchronization with the opening movement of the contact 32, advantage is taken of the proximity of the contact operating linkage 35 and the offset close coupled arrangement of the valve 33 with respect to the contacts 32 and 63. To this end, the bottom flange 77 of the main contact housing 69 is provided with an opening 86 through which an actuating rod 87 extends. A bushing 88 provides an ovally contoured guide hole which accepts the chordal displacement of rod 87. At its inner or upper end the rod 87 is pivotally connected to an arm of a rocker 89 which is pivotally secured between spaced apart lugs 91, one of which is shown. The opposite arm of the rocker 89 is pivotally connected to a rod 92 which, in turn, is pivotally connected to a member of the operating linkage 35. To maintain the actuating rod 87 clear of the valve 33 so that a valve closing spring 93 is freely operative to return the valve 33 to a closed position, one end of a rocker spring 94 is attached to the arm of the rocker 89 with the opposite end of the spring 94 being attached to a fixed stud 96. Thus, the spring 94 operates to exert a constant bias on the rocker 89 for urging it in a clockwise direction, as viewed in FIG. 3, thereby lifting the rod 87 free of the valve 33.

As previously indicated, the contact and blast valve unit 26 is a plug-in unit which can be inserted into operating position or withdrawn from the ends of the tank 31. To this purpose the lower right end 101 of the valve elbow 76 is formed with a circular tapered leading edge 102. The circular leading edge 102 of the elbow mates with a circular outlet portion 103 of a T-shaped gas distribution header 104. Header 104 operates to receive the gas from the supply pipe 38 and to direct the gas leftwardly and rightwardly to both of the contact and blast valve units 26 and 27. As shown, an O-ring 106 is engaged on the external surface of the header outlet portion 103 and serves to seal the joint space therebetween.

For guiding and controlling the position of the circular tapered leading edge of the valve elbow 76 as it is moved inwardly to engage on the outlet portion 103 of the T-header 104 there is provided a positioning guide 107. The positioning guide 107 is herein shown as a stud threadedly engaged in a horizontally extending ear portion 108 formed integrally with the base flange of the T-header 104. The extending end of the guide stud is formed with a ball 109 on which the elbow will engage and slide. By adjusting the axial position of the guide stud 107, the elevation at which the circular tapered leading edge 101 of the elbow 76 approaches the circular outlet portion 103 of the T-header can be established.

For securing the contact and blast valve unit 26 in good conducting engagement with the central housing member 28, a unique conducting and tolerance equalizing means 110 is provided. As shown in FIGS. 3, 4 and 5, the main contact housing 69 is provided with a projecting pad member 111. The forward face 112 of the pad member 111 is machined to provide for good electrical contact against an adjacent conducting and support means 114 provided on the central housing member 28. Since in manufacturing components such

as the main contact housing 69 and the central housing 28 tolerance variations are likely to occur, the conducting and support means 114 is self-adjusting to compensate for such tolerance variations and to make good conducting contact with the face 112 of pad 111. To this end, as shown in FIG. 5, the member 114 is formed as an adjustable pad or washer 116 having a semispherical rear surface 117 which seats within a complementary cavity 118 formed in the central housing member 28. For maintaining the adjustable conducting washer 116 in position, a bolt 119 is employed. The bolt 119 extends through a suitable opening in the washer 116 and a complementary opening in the wall of the central housing member 28. A compression spring 121 is engaged on the threaded end of the bolt 119 and abuts the inner surface of the central member 28 and a nut 122 on the bolt 119. By adjusting the nut 122 on the bolt 119 the spring 121 will apply a desired amount of force to the bolt to maintain the pad or washer 116 adjustably seated within the cavity 118.

Thus, with insertion of the contact and blast valve unit 26 into operating position, the tapered circular edge 102 of the elbow 76 will engage on the circular outlet portion 103 of the T-shaped gas supply header 104 being guided thereon by the guide support 107. With engagement effected between the elbow 76 and the outlet 103 of the gas supply header 104 the conducting pad 111 will engage the adjustable conducting washer 116 to establish the main electrical conducting path between the central housing 28 and the contact and blast valve unit 26. Thus, the elbow 76, passage 79 of main casting 69 and gas flow chamber 81 define an offset gas flow channel between the distribution supply header 104 and the area of arcing.

To secure the contact and blast valve unit 26 in operative position, the elbow 76 is removably fastened to the T-shaped gas supply header 104. To this end, as depicted in FIGS. 3, 4 and 6, the elbow 76 is provided with a pair of laterally extending ears 126 (see FIG. 11), one being indicated by broken lines in FIGS. 3 and 4. The ears 126 are formed integrally with the elbow structure being spaced on either side thereof. A bolt 127 extends through a suitable opening in the ear 126 and threadedly engages in a threaded blind bore 128 provided in a laterally extending flange 129 formed on the header 104. It will be understood that the gas supply header 104 is provided with two bolt receiving flanges, one on each side, with the far side flange 129 being depicted by broken lines in the drawings.

An elbow securing arrangement is shown in detail in FIG. 6. As there shown the lateral extending ear 126 is provided with a threaded bore 131 which receives a threaded axially adjustable stop sleeve 132. The stop sleeve 132 operates to establish the amount of interengagement that will be established between the elbow and the outlet 103 of the header 104. Thus, the sleeves operate to establish the desired orientation of the contact and blast valve unit 26 with respect to the tank 31, the central housing member 28 and the gas supply header 104. For adjusting the stop sleeve 132 axially within the bore 131 the end of the stop sleeve is provided with a slot 133 in which a snap-in tool 141A can engage to effect the desired axial adjustments thereof. The stop sleeve 132 is provided with an axial bore 134 through which the bolt 127 and its companion bolt (not shown) extends to threadedly engage in the flange 129 and 129A, FIG. 11, of the housing 104. A counterbore

136 is provided to receive a bearing washer 137 against which the head 138 of the bolt 127 engages.

Since the locations of the bolts 127 are not conveniently accessible from the end of the tank 31, a long handle wrench 139 is provided for engaging or disengaging the bolts 127 and the sleeves 132. As shown in FIG. 6, the wrench 129 is provided with a head portion 141 internally configured to match the external configuration of the bolt head 138 and the tool 141A. A laterally operating bolt head engaging detent 142 is provided on the wrench head 141 for holding the bolt or tool to the wrench. As shown, the detent 142 is biased inwardly by means of a leaf spring 144. Thus, as the wrench 139 is rotated to withdraw the bolt or tool from securing engagement with the flange 129, the head 138 of the bolt 127 or tool 141A will be locked within the wrench head 141 by operation of the detent engaging in a peripheral annular groove formed on the bolt head 138. With this arrangement the possibility of a bolt or tool, such as the bolt 127, being accidentally dropped into the interior of the tank is eliminated. The importance of securing the bolt 127 or tool to the wrench 139 is more apparent when it is considered what trouble and cost is entailed should a bolt be accidentally dropped into the tank 31, especially in the area of the high pressure tank. If a bolt is accidentally dropped, it must be recovered before the circuit breaker can be put into operation. Thus, to recover a bolt either the circuit breaker must be removed to allow service personnel to crawl into the tank 31 or the high pressure tank 36 must be removed. In either case, a loss of time with the accompanying cost is experienced.

With the contact and blast valve unit 26 secured to the gas supply header 104, the upper portion of the unit 26 is secured to the central housing or member 28. To this end the contact pad 111 is provided with laterally extending flanges 146 and 146A as shown in FIG. 5. Each flange is provided with a pair of vertically spaced bolt passages or slots 147, 147A and 148, 148A through which securing bolts 149 extend. The bolts engage in suitable aligned threaded bores formed in a boss 150 formed on the central housing 28. Thus, linear tolerance variation in the contact pad 111 will be compensated for by the vertical slot openings. In tightening the bolts 149, the face surface 112 of the contact pad 111 will engage the adjustable washer 116 and the washer will adjust within the cavity 118 to accommodate for angular tolerance variation and to insure good electrical contact therebetween. A bolt 149 if accidentally dropped into the tank 31 will be extremely difficult to recover. To do so will entail removal of the contact and blast valve unit 26 so that a serviceman can crawl into the tank. To prevent accidental displacement of a bolt 149 from out of an associated slot 147, 147A, 148 and 148A, there is provided capturing means for returning a bolt to the slot. To this end, as shown in FIG. 5, each bolt is provided with a washer 151 which is larger in diameter than the width of the slot 147 through which it extends. Engaged on the shank of the bolt 149 and disposed between the washer 151 and the threaded end of the bolt is a retainer which in its simplest form can be an O-ring 152. Thus, as the bolt 149 is disengaged from the boss 150, the bolt is retained within the associated slot 147 by the washer 151 and the O-ring 152 which is prevented from slipping off of the bolt by the bolt threads. The washer 151 on the other hand effectively prevents the O-ring

152 from passing through the slot. Thus, the bolts 149 are effectively captured within their respective slots. Access to the bolts 149 from the exterior of the tank 31 for engaging or disengaging them into or out of securing relationship is afforded by means of sealed ports 153 and 153A both of which have removable sealing covers 154 and 154A.

As mentioned, it is necessary to assemble and service the contact and blast valve unit 26 exteriorly of the tank 31. To facilitate the insertion and withdrawal of the contact and blast valve unit 26 into and out of the tank 31 through the end of the tank with a minimum of manpower and space at the tank end, a service unit 155 is provided. As shown in FIGS. 2, 7, 8, 9 and 10, the service unit 155 is provided with a pair of spaced external cantilever guide rail supports 156 and 156A. The cantilever supports 156 and 156A are demountably attached to the lower ends of associated vertical angle members 157 and 157A. The angle members 157 and 157A are removably bolted to the tank end door flange 158. A pair of horizontally spaced rail members 159 and 159A have their inner or tank ends bolted to support blocks 161 and 161A carried by the vertical angle members 157 and 157A, respectively. The outboard ends of the rails 159 and 159A are bolted to the cantilever support rail supports 156 and 156A. Within the tank 31 there is an auxiliary pair of spaced guide members 162 and 162A which constitute extension of the outboard rails 159 and 159A, respectively. For operatively supporting the inboard rails 162 and 162A within the tank 31 the forward ends of the rails 162 and 162A are each formed with a bayonet type projection 163 and 163A, respectively. For receiving and supporting the inboard ends 163 and 163A of the rails 162 and 162A the central housing member 28 is provided with horizontal laterally extending center supports 164 and 164A. The bayonet ends 163 and 163A of the inboard rails 162 and 162A engage on the center supports 164 and 164A, respectively, while the outer or left ends of the rails 162 and 162A, as viewed in FIGS. 7, 8, 9 and 10, are bolted to the support blocks 161 and 161A, respectively. As depicted in FIGS. 7, 8, 9 and 10, the inboard rails 162 and 162A in operative position are disposed below horizontal lateral projections 166, 166A and 167, 167A provided on each side of the corona shields 73 and 73A, respectively. Thus, with the contact and blast valve unit 26 released from the central housing member 28 and header 104 the unit 26 is carried on the rails 162 and 162A.

For withdrawing the contact and blast valve unit 26 from the tank 31, a winch device 168, as shown in FIGS. 7 and 8, is provided. The winch device 168 is mounted at the extreme outer ends of the outboard rails 159 and 159A on a horizontal cross member 169 which ties the spaced rail members together. For withdrawing the contact and blast valve unit 26 out of the tank 31 along the rails, the winch device 168 includes a worm and worm wheel drive 171 that is carried in a bracket 172 mounted on the cross member 169. A drum 173 mounted in coaxial relationship to rotate with the worm wheel member of the winch has a wire rope 174 connected thereto. The wire rope 174 travels over a horizontal idler pulley 176 which is mounted for rotation on the cross member 169. The free end of the wire rope 174 is provided with an attaching means such as a hook 177 by which it is releasably connected to the end of the contact and blast valve unit 26. Rotation of

the drum 173 by operation of a hand crank 179 will wind the wire rope 174 on the drum 173. This will cause the unfastened contact and blast valve unit 26 to move along the rails from the position it occupies, as depicted in full lines, to a position outside of the tank 31, as depicted by broken lines in FIG. 8. By establishing the rails on an incline plane, the contact and blast valve unit 26, as it moves along the rails, is gradually moved upwardly so that the bottom curved surface of the elbow 76, as viewed in FIG. 4, will clear the tank. With the contact and blast valve unit 26 in withdrawn position on the outboard rails 159 and 159A, servicing of the unit can be accomplished or it may be removed and a new unit substituted.

To insert the contact and blast valve unit 26 into operating position with the tank 31, its guided movement along the rails 159 and 159A is initiated manually by pushing it along the rails. However, the further the unit 26 is moved along the rails into the tank 31 the more difficult it becomes to exert the degree of leverage necessary to keep the unit moving. Also, the engagement of the elbow 76 on the outlet 103 of the gas supply header 104 requires an additional force to effect a sealing mating engagement with the O-ring 106. To provide the additional force that is required, an inserting toggle device 185 is provided, as shown in FIGS. 9 and 10. As there shown, the toggle device 185 comprises a breakable frame including a rightwardly disposed V-shaped thrust member 186. The bifurcated left end of the thrust member 186 is pivotally mounted on a bar member 187 which also pivotally receives the forward or rightwardly disposed ends of a base member 188. The rear or left end of the base member 188, as viewed in FIGS. 9 and 10, are pivotally connected to a horizontal bar 189 that is removably disposed within aligned openings formed in the sides of the rails 159 and 159A. A quick release connection arrangement is provided on the forward end of the thrust member 186 to simplify the disengagement of the toggle device 185 from the contact and blast valve unit 26 after it has been moved into operative position. To this end the forward end of the thrust member 186 is formed with a downwardly inclined slot 191 which is adapted to engage on a pin 192 carried in a pair of spaced projections or lugs 193 provided on the contact and blast valve unit 26.

In operation, let it be assumed that the contact and blast valve unit 26 has been moved along the service unit 155 to a position where it is partially within the tank 31. At this point the toggle device 185 is positioned on the service unit 155 and the bar 189 inserted through the opening in one rail and through the ends of the thrust member 188 and thence through the opening in the opposite rail. The quick release connection 191 is engaged on the pin 192. At this time the toggle device will be broken with the mid portion including the bar 187 being in an elevated position. The operator will apply a downwardly acting force to the bar 187 to collapse the toggle device 185 forcing the contact and blast valve unit 26 in a guided path of travel along the downwardly inclined inner rails 162-162A into its operating position. As the contact and blast valve unit 26 moves into its operating position the approach elevation of the tapered inlet 102 relative to the outlet opening 103 will be guidably established by the positioning guide 109, FIGS. 3 and 4, so that positive sealed mating engagement is effected.

After the insertion of the contact and blast valve unit 26 into its operating position has been accomplished the toggle device 185 is disconnected from the unit 26 and dismantled from the service unit 155. The service unit 155 is then unbolted from the door flange 158 of the tank 31 and removed. The hinged door, FIG. 2, is closed and secured.

In FIG. 12 the circuit breaker has been illustrated as it would be modified for a particular installation requiring minimal initial interrupting capacity but which can be readily and inexpensively expanded at a future time.

To this end, the rightwardly disposed gas supply outlet 196, as viewed in FIG. 12, is blocked by a cap 197. The cap 197 is secured over the header outlet 196 by means of screws (not shown) which register in suitable openings provided in flanges 198. The flanges 198 are identical to the flanges 129 to which the elbow 76 is secured.

For effecting continuity in the electrical circuit from the interrupter unit 26 via the central housing 28, there is provided a conductor 199. The conductor 199 is provided with a contact pad 201 similar to the pad 111 associated with the interrupter unit 26. Screws 203 inserted through the pad 201 threadedly engage in the mounting abutment 204 to secure the conductor contact pad 201 in good electrical contact with an adjustable washer 206. The opposite end of the conductor 199 (not shown) is operatively connected to the bottom of the bushing stud such as the bushing 208 depicted in FIG. 1.

The modified arrangement of FIG. 12 provides great flexibility and also provides economies to the purchaser allowing him to install units of minimal interrupting capacity and thereafter to expand the interrupting capacity as required.

The embodiment of the invention in which an exclusive property or privilege is claimed are defined as follows:

1. In a gas-insulated circuit breaker:
a circuit breaker tank having a service opening;
a contact and blast valve unit insertable through the service opening in said tank into operative position in said tank;
a gas supply distribution member supported within the interior of said tank;
an outlet formed on said distribution member;
a tapered inlet formed in said contact and blast valve unit to cooperate with said outlet of said distribution member; and,
an O-ring carried by said outlet for effecting a gas-tight seal between said outlet and inlet when mating engagement is effected between said inlet and outlet upon insertion of said contact and blast valve unit into operating position within said tank.
2. A gas-insulated circuit breaker according to claim 1 wherein there is provided guide means to guide said contact and blast valve unit as it is inserted into operating position in said tank.
3. In a circuit breaker:
a tank;
a support housing carried by said tank in the interior thereof;
a contact and blast valve unit having a fastening block for securement to said support housing, said fastening block also serving as an electrical con-

ductor between said contact and blast valve unit and said support housing; and,
a conducting self-adjusting ring carried by said support member in position to be engaged by said fastening block when said contact and blast valve unit is inserted into operative position within said tank.

4. A circuit breaker according to claim 3 wherein said fastening block is provided with a slotted opening through which fasteners are inserted to engage in said support housing; and,

capturing means associated with said fasteners and cooperable with said fastening block to retain said bolts within said slots when said fasteners are not engaged in said support housing; whereby said fasteners are readily accessible for engagement in said support housing and are prevented from accidental dislodgment from said slots when not engaged.

5. In a circuit breaker:

a tank;

a support housing within said tank;

a contact and blast valve unit comprising an insulator housing in which a fixed main contact is located; a main contact housing having a movable contact support projection in which a movable main contact is disposed for axial movement, said support projection extending into said insulator housing in annularly spaced relationship to thereby define an annular gas passage; an annular gas passageway formed in said main contact housing around said projection in position to communicate with the annular gas passage formed between said projection and the interior of said contact housing;

a gas supply passage formed in said main contact housing in communication with said annular passage formed in said main contact housing, said gas supply passage also communicating with the end of said main contact housing;

a hollow elbow secured to the end of said main contact housing and having communication with said gas supply passage, the opposite end of said elbow forming a gas inlet, the axis of which is substantially parallel to the axis of said insulator housing;

a gas supply distribution member within said tank, said distribution member having an outlet which mates in sealed relationship with the inlet of said elbow; and,

a valve within said elbow normally operable to seal the communication connection between said elbow and said gas supply passage in said main contact housing.

6. In a gas-insulated circuit breaker:

a circuit breaker tank having a service opening; a contact and blast valve unit insertable through the service opening in said tank into an operative position therein, said contact and blast valve unit having a gas inlet portion;

a gas supply distribution means supported within said tank, said distribution means having an outlet portion complementary to said gas inlet portion of said contact and blast valve unit; and

guide means operable to control the elevation of the gas inlet portion of said contact and blast valve unit to establish substantial alignment of the inlet por-

tion relative to the complementary outlet portion of said distribution means so that mating engagement between the complementary inlet and outlet portions will occur as said contact and blast valve unit is inserted into operative position in said tank.

7. A gas-insulated circuit breaker according to claim 6 wherein the complementary inlet and outlet portions are of annular configuration and one of said portions is provided with an annular tapered edge for facilitating the mating engagement between said portion.

8. A gas-insulated circuit breaker according to claim 6 wherein said guide means is a ball guide supported for axial adjustment and in position to engage the bottom surface of said contact and blast valve unit as said unit is moved into operative position within the tank.

9. A gas-insulated circuit breaker according to claim 6 wherein one of said portions carries a seal operable to seal the joint space between said complementary inlet and outlet portions when mating engagement therebetween is effected.

10. In a gas-insulated circuit breaker:

a circuit breaker tank having a service opening; a contact and blast valve unit insertable through the service opening in said tank into an operative position therein, said contact and blast valve unit having a gas inlet;

a gas supply distribution member supported within said tank and having an outlet complementary to the inlet of said contact and blast valve unit for mating engagement with said outlet; and, guide means operable to control the lateral direction and the elevation of said contact and blast valve unit to establish substantial alignment of said inlet relative to said outlet so that mating engagement between said inlet and outlet will occur as said contact and blast valve unit is inserted into operating position within said tank.

11. In combination:

a circuit breaker tank having a service opening; a support member carried by said tank within the interior thereof;

a contact and blast valve unit removably attached at one end to said support member;

an interior rail support extending between said support member and the service opening, said interior rail support having its inner end restably confined on said support member, the outer end of said interior rail support being detachably supported by said tank at a position adjacent the service opening and at an elevation above the level at which the inner end of the rail support is supported;

an exterior rail support detachably secured in cantilever relationship to said tank, said exterior rail support extending away from the opening in said tank to provide an external support for a contact and blast valve unit, said exterior rail support being in alignment with said interior rail support and having the same grade as said interior rail support; and,

a breakable A-frame member having one leg releasably attached to said exterior rail support and its opposite leg releasably connected to said contact and blast valve unit;

whereby collapsing of said A-frame impels said contact and blast valve unit along said rails supports and into operating engagement with said support member.

12. In a gas circuit breaker:

casing means defining an arcing chamber and having a communicating gas flow directing annular orifice portion for directing gas under pressure to said arcing chamber;

a stationary contact structure having a gas exhaust opening associated therewith extending within said casing means;

a movable tubular contact having a gas exhaust opening therethrough and cooperable with said stationary contact structure in said arcing chamber of said casing means;

means defining a gas receiving chamber surrounding said movable contact in communication with said gas flow annular orifice portion of said casing means;

a pressurized gas chamber angularly offset relative to said gas receiving chamber surrounding said movable contact and having gas under pressure therein;

a gas supply passage between said pressure gas chamber and said gas receiving chamber; and,

valve means in said pressurized gas chamber normally operable to seal the opening between said gas supply passage and said pressure gas chamber.

13. A gas circuit breaker according to claim 12 wherein said casing is provided with a pocket rearwardly of the gas exhaust opening of said movable contact; and,

means operable supported in said pocket out of the direct path of said gas exhaust opening of said movable contact for actuating said valve to open position to allow pressure gas to flow from said pressure gas chamber into said communicating gas supply passage.

14. A gas circuit breaker according to claim 13 wherein there is provided operating means connected to effect synchronized opening movement of said movable contact and operation of said valve actuating means;

whereby pressure gas is directed to said arcing chamber in said casing substantially at contact parting to extinguish the arc drawn between said contacts.

15. In a gas blast circuit breaker:

a circuit breaker tank;

a support mounted within said tank;

a contact and blast valve unit having single upper support bracket for securing said contact blast valve unit to said support housing; and,

a pair of spaced apart lower securing means disposed towards the bottom of said contact and blast valve unit on each side thereof, said pair of securing means being engageable in said support housing to secure the bottom portion of contact and blast valve unit to said support;

whereby said contact and blast valve unit is secured in operative position within said tank with three point suspension.

16. A gas blast circuit breaker according to claim 15 wherein:

said single upper support bracket is a main electrical conducting member;

said support housing is provided with a self-adjusting electrical conducting washer adapted to be engaged by said upper support bracket;

said spaced apart lower securing means each include an axially adjustable sleeve having a bore opera-

tively carried by the lower portion of said contact and blast valve unit; and,

a bolt extending through the axial bore in said adjustable sleeve into threaded engagement with said support housing, said bolt having abutment means engageable with said contact and blast valve unit but does not engage said sleeve, said bolts operating to secure the bottom portion of said contact and blast valve unit but does not engage said sleeve, said bolts operating to secure the bottom portion of said contact and blast valve unit to said support housing and also to lock an associated sleeve in an adjusted position;

whereby each sleeve of said lower securing means can be adjusted individually to adjust the position of said contact and blast valve unit within said tank and said self-adjusting washer compensates for angular variation.

17. In a gas blast circuit having:

a tank; and,

a contact and blast valve unit operatively disposed within said tank, said contact and blast valve unit comprising:

a casing defining an arcing chamber and into which gas under pressure is to be supplied;

a fixed tubular contact in said casing with the bore thereof operating as an exhaust passage to vent a portion of the gas supplied to said arcing chamber to said tank;

a movable tubular contact supported within said arcing chamber in coaxial cooperating relationship to said fixed contact, the bore of said movable contact operating as an exhaust passage;

a source of gas under pressure;

a pressure gas chamber connected to receive gas under pressure from said source;

an annular gas directing chamber surrounding said movable contact to direct gas under pressure to said arcing chamber, said annular gas directing chamber defining a gas exhaust passage into which the bore of said tubular movable contact vents in a straight line path;

a gas flow passage in communication with said annular gas directing chamber but angularly offset therefrom, said gas flow passage also having communication with said pressure gas chamber;

means normally operable to block the flow of gas under pressure from said pressure gas chamber to said gas flow passage; and,

means for actuating said blocking means from its normal operating position to permit gas under pressure to escape as a blast from said pressure gas chamber into said gas flow passage, said actuating means being disposed in said gas exhaust passage defined by said annular gas directing chamber but substantially offset from the direct line of exhaust gas flow.

18. In a gas-insulated circuit breaker:

a circuit breaker tank;

a gas supply tank supported by said circuit breaker tank;

a gas supply distribution member in communication with said gas supply tank, said gas supply distribution member having at least one outlet;

a contact and blast valve unit supported in operative position within said tank;

an offset gas flow channel between said distribution member and an arcing area, the end of said offset gas flow channel adjacent said distribution member defining an inlet constructed and arranged to cooperate with the outlet presented by said distribution member, the arrangement being such that said inlet and outlet cooperate to effect a mating engagement therebetween; and,

sealing means carried by said outlet to effect a gas-tight seal between said inlet and outlet when mated.

19. In combination:

a circuit breaker tank having an opening through which servicing can be accomplished;

a support member carried by said tank within the interior thereof;

a contact and blast valve unit removably connected to said support member;

a pair of internal spaced apart rail members extending between said support member and the opening in said tank in position to guidably support said contact and blast valve unit for movement into and out said tank, said internal rail members being disposed in a manner to direct said contact and blast valve unit as it is moved into said tank into operative engagement with said support member;

laterally extending holding means on said support member to freely demountably receive the inboard ends of said internal rail members, the arrangement being such that said internal rails may be inserted through the opening in said tank with the inboard ends of said rails freely engaging said laterally extending holding means for securely supporting the inboard ends of said rails;

removable means at the opening of said tank to secure the outboard ends of said internal rail members; and,

a pair of external spaced apart rail members extending away from the opening in said tank, said external pair of rails being detachably carried by said

tank in cantilever relationship, whereby said contact and blast valve unit supported on the external rail members will be moved along said external rail members into said tank and on said internal rail members to be supported and guided thereby into operative association with said support member.

20. In a gas insulated circuit breaker:

an elongated circuit breaker tank;

a gas supply tank supported by said circuit breaker tank midway of the ends of said circuit breaker tank;

a gas supply distribution member in communication with said gas supply tank and extending upwardly therefrom into said circuit tank, said gas supply distribution member having two outlets arranged to direct gas flow towards each end of said circuit breaker tank;

a contact and blast valve unit supported in operative position in one end of said circuit breaker tank;

a gas inlet formed in said contact and blast valve unit in position to cooperatively interengage with an adjacent outlet of said distribution member;

sealing means carried by said outlet of said distribution member to effect a gas-tight seal between said outlet and said inlet of said contact and blast valve unit; and,

means operatively engaged to said other outlet of said distribution member to seal said outlet to thereby direct all gas flow from said distribution member through the outlet associated with said contact and blast valve unit,

whereby said nonutilized outlet of said distribution member is available to receive the inlet of another contact and blast valve unit for subsequently increasing the interrupting capacity of said circuit breaker without additional modification of the circuit breaker.
